UNITED STATES PATENT OFFICE

GRANVILLE S. RIDER, OF FLUSHING, NEW YORK, ASSIGNOR TO NATHAN SCHOENTHAL, OF NEW YORK, N. Y.

LATCH OPERATING MEANS FOR DIRECTORY BOARDS, ETC.

Application filed February 7, 1930. Serial No. 426,475.

My invention relates to directory, card or sign exhibiting structures, and especially to new and improved means for locking or latching hinged exhibiting panels or analogous structures in a main frame, with new and improved means for operating the locking or latching devices.

The exhibiting panel or analogous structure is generally similar to those shown in 10 companion applications executed on even date herewith, and the present application relates particularly to latching means and latch operating means of an improved type especially applicable to such movable or hinged panels or analogous devices, in which preferably there is no external knob or handle and which are devised to discourage or practically prevent unauthorized tampering and especially opening of the panels and manipulation of 20 the data cards or analogous movable elements therein.

To these ends the invention structure comprises latches internally located on the panel or like hinged structure, and engaging members of the main frame, with latch operating means or mechanism which is devised to have the outward semblance of a keyed lock, but is incapable of operation by any ordinary or skeleton key or appliance similar to or manipulated in the manner of a key, but which may be operated by an authorized or informed person merely by insertion of a simple rod-like implement such as a nail; or if desired, alternatively by the use of a screw 30 driver or equivalent instrument.

The characteristics and advantages of the invention are further sufficiently explained in connection with the following detail description of the accompanying drawings, which 40 show one representative embodiment. After considering this example, skilled persons will understand that many variations may be made without departing from the principles disclosed and I contemplate the employment 45 of any structures that are properly within the scope of the appended claims.

Fig. 1 is a partial front perspective view of a structure embodying the invention in one form.

Fig. 2 is a vertical section through a typi-

cal main frame showing the exhibiting panel or equivalent structure in edge view and in closed position.

Fig. 3 is an enlarged fragmentary front view of the part of the panel carrying the latch operating device.

Any suitable main or outer frame structure may be provided, including as here shown, facing strips 1, and inwardly directed strips or flanges 2, 3 and 4, extending therefrom and forming respectively the sides, top and bottom of a main or central aperture to receive one or a plurality of exhibiting panels 4 or analogous structures. The main frame also has one or a plurality of transverse strips 5 across the aperture substantially at the rear thereof.

Each of the one or more panels 4 has at one side, at top and bottom, outwardly projecting or offset hinge lugs 6 for the pivotal or hinge mounting of the panel in the main frame as by hinge pins 7 secured therein, or as more fully set forth in the above identified application. At the back of the panel, and at its free side are one or more locking or latching devices. Two are here shown, to cooperate with the upper and lower back strips 5, but after reading the following description it will be understood that one of the latches and connecting parts (specifically the upper latch and its link) may be omitted and in such cases the other latch may, if desired, cooperate with a strip such as 5, located near the horizontal center of the structure instead of in a lower position as here shown.

In the present arrangement the lower latch 8 is pivotally mounted at 9 in a lug 10 on the frame side member. The latch comprises a latch arm proper 11 having a hook 12 with a leading beveled face 13. The hook cooperates with the lower transverse frame strip 5 in an obvious way, as shown in Figs. 1 and 2, and for cooperation with the beveled latch face 13 as the panel is closed, the upper face of the strip may be rounded or beveled as at 14 although this is not essential. The latch also has an arm 15 acted on by a spring 16 seated in sockets in the panel and in the arm respectively, urging the main latch arm to active position.

The latch structure also has another, depending, releasing arm 17.

To operate the latch the free side member of the panel has opposite arm 17 a hole 20, and in a simplified form of the invention this hole may be of small diameter, adapted to admit a small rod-like implement, such as a wire nail, which when inserted through the hole will engage arm 17 or a filler piece or pad 18 thereon, to raise the latch proper 11, and thus release the hook from engagement behind the strip 5, whereupon the panel may be swung open with or without the aid of a spring device, as disclosed in one of the aforesaid applications.

In a preferred arrangement however, as here shown, the hole 20 may be internally threaded and a tubular screw 21 inserted therein. This tubular screw provides a center bore through which a nail or similar implement may be inserted to operate the latch in the manner above described.

The outer end of the screw has at opposite sides kerfs or notches 22 to receive a screw driver or analogous implement. The latch may then be operated by inserting the screw driver bit in the screw notches and turning until the inward movement of the screw in contact with arm 11 or its pad 18 releases the hook.

Whether the latch operating means consists of a simple hole or a tubular screw, in preferred cases I provide the hole or bore 20 at its outer end with inwardly cut opposite slots or notches 23, so that the external appearance of the hole or aperture is similar to that of a keyed lock. As otherwise described, the latch operating opening is camouflaged so that unauthorized or uninformed persons will believe that the panel can be opened only by the use of a special key and will not make the attempt, or if they do attempt to open it by key manipulation, such manipulation will be ineffective, and such unauthorized persons will not understand that the latch may be released by a simple insertion of a rod or use of a screw driver.

The upper latch 8a, to cooperate with the upper frame strip 5 and afford added locking security, may be identical with the lower latch 8 except that the releasing arm 17 may be omitted; and the two latches are connected by a link 30, so that when the lower latch is manipulated in the manner above described, the upper latch is simultaneously operated.

While the complete structure 4 carrying the latches is above described as an exhibiting panel, it may otherwise be a door arranged in a main frame or casing to enclose one or more panels or card exhibiting frames, as shown in one of the above mentioned applications, and in such cases the latch mechanism may be applied to the door. In certain of the appended claims therefor the term "an exhibition panel or the like" is

in its broad sense inclusive of a door pivotally mounted in the main frame or casing.

I claim:—

1. In a structure of the character described, a frame having an opening for an exhibition panel or the like, a panel pivotally mounted therein, a latch pivotally mounted at the inner side of the panel and cooperating with a fixed frame member, the latch having a releasing arm and the panel having therethrough an internally threaded hole, and a screw in the hole confronting the latch releasing arm for latch release by rotation of the screw. 70

2. In a structure of the character described, a frame having an opening for an exhibition panel or the like, a panel pivotally mounted therein, a latch pivotally mounted at the inner side of the panel and cooperating with a fixed frame member, the latch having a releasing arm and the panel having therethrough an internally threaded hole, and a tubular screw in the hole, whereby the latch may be released by screw rotation or by insertion of a rod-like implement through the screw. 80

3. In a structure of the character described, a frame having an opening for an exhibition panel or the like, a panel pivotally mounted therein, a latch pivotally mounted at the inner side of the panel and cooperating with a fixed frame member, the panel having therethrough an aperture giving access to the latch for release of the latch by an element moved within the aperture, and another substantially similar latch cooperating with another fixed frame member, and an operating connection from one latch to the other. 95

4. In a structure of the character described, a frame having an opening for an exhibition panel or the like, a panel pivotally mounted therein, a latch pivotally mounted at the inner side of the panel and cooperating with a fixed frame member, the panel having therethrough an aperture giving access to the latch for release of the latch by an element moved within the aperture, the aperture having at the outer face of the panel opposite slots giving the semblance of a key aperture, and another substantially similar latch cooperating with another fixed frame member or frame strip, and an operating connection from one latch to the other. 105

5. In a structure of the character described, a frame having an opening for an exhibition panel or the like, one or more horizontal strips crossing the opening, a panel pivotally mounted in the opening, a latch pivotally mounted at the inner side of the panel and cooperating with one of the frame strips, the panel having therethrough an aperture giving access to the latch for release of the latch by an element moved within the aperture. 120

6. In a structure of the character described, a frame having an opening for an exhibition panel or the like, one or more horizontal strips crossing the opening, a panel
 5 pivotally mounted in the opening, a latch pivotally mounted at the inner side of the panel and cooperating with one of the frame strips, the panel having therethrough an aperture giving access to the latch for release
 10 of the latch by an element moved within the aperture, and a spring urging the latch to engaged position.

7. In a structure of the character described, a frame having an opening for an exhibition panel or the like, one or more horizontal strips crossing the opening, a panel pivotally mounted in the opening, a latch pivotally mounted at the inner side of the panel and cooperating with one of the frame strips, the panel having therethrough an aperture giving access to the latch for release
 15 of the latch by an element moved within the aperture, the aperture having at the outer face of the panel opposite slots giving the
 20 semblance of a key aperture.

8. In a structure of the character described, a frame having an opening for an exhibition panel or the like, one or more horizontal strips crossing the opening, a panel
 30 pivotally mounted in the opening, a latch pivotally mounted at the inner side of the panel and cooperating with one of the frame strips, the latch having a releasing arm and the panel having therethrough a hole aligned
 35 with the arm and permitting latch release by insertion of a rod-like implement through the hole.

9. In a display structure for purposes described, a frame having an opening for an exhibition panel or the like, a panel pivotally mounted therein on a vertical axis, upper and lower latch abutments supported by the frame, and upper and lower latches pivotally mounted on the panel to cooperate
 40 with the abutments, spring means urging the latches to engagement and a link connecting the latches to move together, one of the latches having a releasing arm and the panel having confronting the arm an aperture providing for insertion therethrough of a rod like implement to engage said arm and release the latches.

10. The structure defined in claim 9 with the addition that the panel aperture is threaded, and a screw is located in the threaded aperture with its inward end confronting the releasing arm and its outer end accessible for rotation by a screw driver.

11. The structure defined in claim 9 with the addition that the panel aperture is threaded, and a screw is located in the threaded aperture with its inward end confronting the releasing arm and its outer end accessible for rotation by a screw driver, the screw

being tubular, admitting insertion of a rod like implement to engage the releasing arm.

In testimony whereof I have affixed my signature.
